UNITED STATES PATENT OFFICE.

ZURIEL SWOPE, OF LANCASTER, PENNSYLVANIA.

IMPROVEMENT IN HARVESTERS.

Specification forming part of Letters Patent No. 136,279, dated February 25, 1873.

To all whom it may concern:

Be it known that I, ZURIEL SWOPE, of Lancaster, in the county of Lancaster and in the State of Pennsylvania, have invented certain new and useful Improvements in Field-Mower; and do hereby declare that the following is a full, clear, and exact description thereof, reference being had to the accompanying drawing and to the letters of reference marked thereon, making a part of this specification.

The nature of my invention consists in the construction and arrangement of a field-mower, as will be hereinafter more fully set forth, and which is also intended and adapted for harvesting by connecting therewith a quadrant, as well as any of the ordinary rakes now in use.

In order to enable others skilled in the art to which my invention appertains to make and use the same, I will now proceed to describe its construction and operation, referring to the annexed drawing, in which—

Figure 1 is a plan view, and Fig. 2 a side elevation, of my machine. Figs. 3 and 4 are detached views of certain parts thereof, and Fig. 5 shows a part of the cutter-bar when the machine is used as a harvester.

A A represent the side pieces of the framework of my mower, said side pieces being each a skeleton frame of the peculiar form and construction shown in Fig. 2. These side pieces or skeleton frames are connected at the rear by a cross-bar, B, and at the front by cross-bars B¹, B², and B³. C is the driving axle, which passes through the lower rear part of the frame, and is upon each end provided with a driving-wheel, D. The axle C and wheels D are provided with the usual pawl-and-ratchet arrangements a, whereby the wheels will turn the axle when moving forward, but turn on the axle while moving backward. Upon the axle C, within the frame, is a spur-wheel, E, which gears with a spur-pinion, G, on a shaft, H, running parallel with but above and in front of the axle C. On this shaft H is secured a bevel-wheel, J, which gears with a bevel-pinion, b, upon an inclined shaft, d, standing at about an angle of forty-five degrees. On the upper end of the shaft d is a crank, e, moving a pitman, f, which connects with a rocking-lever, K, fastened on or nearly on the middle of the cross-bar B³ by a screw or bolt,

allowing the lever to rock on the same. The rocking-lever K, it will be noticed, is, by a pitman, h, connected with the cutter-bar L. This pitman lies in a contrary direction from the cutter-bar, and is pivoted both to the lever and to the cutter-bar by horizontal pins or bolts, as shown. The finger-bar is hinged on top of the shoe M, and when raised leaves the shoe-rest without being turned. The shoe M is, by a bolt or pin, hinged to a bar, I, projecting from the frame-work of the machine, to enable the point of the shoe to rise in passing over obstructions. For raising the finger-bar a suitable lever may be attached, as is common in such cases.

With my mode of gearing I am enabled to throw the second shaft H and second master-wheel J above the shaft C of the driver, and am enabled to increase the second master-wheel until a sufficiency of speed is obtained.

As an illustration of my arrangement I give the following example: Supposing the driving-wheel is thirty inches in diameter, the circumference will be about ninety-four inches. The speed of the cutter-bar should be such as to enable it to cut that distance in one revolution of the driver. If the speed of my first pinion next to the driver is three and a half revolutions and the second seven, these two multiplied make twenty-four and a half revolutions of the crank to one of the driver; and as the knife cuts to and fro it makes two cuts to one revolution of the crank, which makes forty-nine cuts; and as the cutting length of the blade or section is two and a quarter inches it will make one hundred and ten and a quarter inches that the knife can cut in one revolution of the driver. The circumference of the driver being only about ninety-four inches, it leaves more than fifteen inches gain ahead of the driver.

In my machine I use a third wheel, N, behind the shoe M, which serves as a guide-wheel, to direct the course of the machine and take away the side draft. This objection is entirely overcome by the aid of my guide-wheel. This wheel is carried by a jaw, O, with a perpendicular shaft, k, square at the upper end, and provided with a horizontal lever, P, at this end. This lever is intended to set the direction of the wheel according to the direction in which the machine is to move. On the

under part of the lever P is a pin, *i*, which fits in holes on the cross-bar B¹, upon which it rests. The intermediate portion of the shaft *k* is round between the jaw O and the upper square end to allow it being turned by the lever in its apertures or holes, through which it passes. Above the jaw O on the shaft *k* is a round flat collar, *m*, for the purpose of sinking the wheel and raising the shoe of the machine by means of a bent lever, R, at the lower end of which is an elliptic jaw or aperture, *n*, resting upon the collar *m*. By raising the lever R by its handle the wheel N will sink and raise the shoe M, and the ratchet *p*, suspended from the lever, will hook its teeth into the cross-bar B below the handle of this lever. On the other side of the machine, between the large bevel-wheel J and the frame-work, there is a four-pronged sliding lever, S, which is intended for the purpose of throwing the machine in and out of gear, separating the bevel-wheel J from its pinion *b*, and moving them together again at pleasure by means of a stationary collar, *s*, on the shaft H, between the wheel J and the frame-work next to it. Two of these prongs, X X¹, slide in below the shaft H, and the other two, X² X³, on top, with the collar *s* between them. One of the prongs next to the frame-work should pass through an oblong hole at its lower end to hold it secure to the frame-work, so as to enable the lever to shift in and out of gear, as the collar *s* passes in between the prongs. These prongs are made in an irregular shape, as shown in Fig. 4. When the lever is pushed down the collar *s* is in between the prongs at *y*, and when drawn up it is between them at *z*. The ends of the prongs X¹ and X³ being thicker than those of the prongs X and X², this motion pushes the collar from the frame-work and throws the wheel J out of gear; and when the lever is pushed down, the thicknesses of the prongs being reversed, the collar *s* is pushed toward the frame-work and puts the wheel in gear. At the lower edge of the lever S, between the prongs and the handle, are two notches to hook into a notch in the cross-bar B, upon which it slides, to keep the lever at the point where it is shifted to. The notch next to the handle is intended to hold the lever at its place when the machine is in gear, and the other when out of gear. The shaft H is extended through the frame-work on one side, and over and out past the driving-wheel D a sufficient length to receive propelling gearing for a rake. The ear *t*, extended from the frame-

work out above this extended shaft, is intended for a connecting point for a rake.

This mower can also be changed to be adapted for a harvester. To accomplish this object I unbolt the shaft T from the cross-bar B³, the present front of the machine, and attach them to the cross-bar B at the other end, on which is now placed the driver's seat, by placing the bolts inverted through the apertures in it. In this case the driver's seat will have to be reversed and suspended from an adverse cross-bar or the cross-bar B¹, in which the shaft *d* revolves.

By this means the movement of the machine is changed to a contrary direction. The wheels D D with their ratchets are taken off and changed or transferred from one end of the axle to the other to enable the ratchets to work in a contrary or adverse direction corresponding with the movement of the machine; otherwise the ratchets and pawls would not catch in its movement.

By detaching the shoe, cutter-bar, and knife from the side on which they now are placed, and attaching or bolting them on the other side by means of another bar suspended similar to the bar I, with the exception that it must have a curved elbow extended outward from the machine to bring the shoe beyond the driving-wheel, the change to a harvester cutting in rear is effected. For harvesting or mowing purposes, when cutting in rear the guide-wheel N will be in a lateral direction from the cutter-bar.

Having thus fully described my invention, what I claim as new, and desire to secure by Letters Patent, is—

1. The frame A, bent and angular, as shown, with an upper and lower bar on each side, extending forward from and above the axle C, having wheel E, and connected together by the cross-bars B B¹ B² B³, and provided with the shafts H d, with wheels J, b, and G, all constructed and arranged substantially as and for the purposes herein set forth.

2. The combination of the guide-wheel N, shaft *k* with fork O, lever P with pin *i*, lever R with jaw *n* and ratchet *p*, and the collar *m*, all substantially as and for the purposes herein set forth.

In testimony that I claim the foregoing I have hereunto set my hand this 25th day of September, 1872.
